UNITED STATES PATENT OFFICE.

E. W. WOODRUFF AND G. C. GREEN, OF WASHINGTON, D. C.

IMPROVEMENT IN PAPER-FILES.

Specification forming part of Letters Patent No. 76,872, dated April 14, 1868.

To all whom it may concern:

Be it known that we, EDMUND W. WOODRUFF and GEO. C. GREEN, of Washington city, District of Columbia, have invented certain Improvements in Paper-Files; and the following is a full, clear, exact description thereof, reference being had to the accompanying drawings.

The object of our invention is to provide a convenient file for holding papers and similar articles, which, when not in use, can be folded together so as to occupy but a small space.

Our invention consists in constructing a file for holding papers, in which the several parts are jointed or so joined together as that, when not in use, it can be collapsed or folded up.

To enable others to make and use our improved file, we will proceed to describe its construction and operation, referring by letters to the accompanying drawings, in which—

Figure 1 is a perspective view of the file when folded together. Fig. 2 is a perspective view of the file when in use, with the papers compressed. Fig. 3 is a side elevation of the file, showing the papers released. Fig. 4 is a side elevation of the file, showing the position of the lever-clamp and file-board, when opened for filling with papers. Fig. 5 is a side view of the lever clamp detached. Fig. 6 is a rear view of the same. Fig. 7 is a sectional view of the slotted plate.

The several parts of which the file is composed are a board or plate, A, another board or plate, B, and a third board or plate, C, a lever-clamp, D, a slotted plate, E, hinges F F and G G, and hinged side braces H H. The board or plate A may be made of any desired dimensions, so as to suit the especial purpose for which the file may be intended. The board or plate B may be of the same width as plate A, but should not be as long. It is attached to plate A by means of the hinges G G, in such a manner that the two may be folded together, or when opened form a right angle. The file-board C should be of less width and length than plate B. At or about the center of this the lever-clamp D is attached by means of the pieces F F. The lever-clamp D is made as shown in Figs. 5 and 6. The upper end is T-shaped, and is made to work in the pieces F F, which, with them, forms a

hinge. The lower end has four lugs, a a and b b, upon it, two on each side. The two upper ones, a a, together with the base of the lever, form a thumb-piece. The slotted plate E is of metal, and is ribbed on the under side, so as to give strength with lightness. At each end are pieces c c, which are attached to it transversely, which, while they secure the plate to the board A, strengthen the same. The slotted plate E is fitted into board A, so as to be flush with its surface. A space is left between it and the board A, so as to allow the lugs b b of the lever-clamp to pass freely. The slot runs the entire length of the plate, and is of such width that the lever-clamp D will slide freely in it when desired. At the inner end it is widened to admit the lower lugs b b of the lever-clamp D. At the outer end it is so constructed that the lever-clamp will not come out, but will turn back, as shown in Fig. 4, or forward, as shown in Fig. 1. The side braces or stays H H are of metal, and have a knuckle-joint hinge, at or about the center. The ends of the braces are attached on the sides and at the outer ends of the plates A and B, in such a manner as that, when open, they form a support to them. At the same time they answer to keep the papers in place; but when the plates fold together, the braces fold with them.

To unfold the file for use, the file-board C and lever-clamp D are raised to a perpendicular; then the plate B is raised, and the hinge-braces H H are straightened, when it, with the plate A, forms a right angle. The file is then placed as shown in Fig. 4, with the file-board C turned back. Then the papers can be placed within the file, and the file-board is brought against them, when the clamp holds them in place, as shown in Fig. 2. To loosen them, it is only necessary to press the upper end of the file-board toward the papers, which releases the clamp.

It will be seen that the size of the paper-file may be varied, so as to contain documents and papers of any form or dimensions. It may be made of wood or metal, in any convenient form to combine strength with lightness. Being constructed so as to fold up, it consequently occupies but little room when not in use, thus economizing space and facilitating

transportation; and yet, when in use, it is strong, durable, and not liable to get out of order.

Having thus described our invention, what we claim as new, and desire to secure by Letters Patent, is—

1. A file for holding papers, or other similar articles, with hinged joints, so that it may be folded together when not in use, substantially as set forth.

2. A paper-file, with the clamping device so arranged that the clamp-lever will turn back-

ward or forward, for the purposes specified, without being detached from the file, substantially as shown.

3. Attaching the file-board to the lever-clamp with a hinge, or its equivalent, substantially as shown.
